UNITED STATES PATENT OFFICE.

DAVID A. COREY AND HERBERT J. GROSVENOR, OF FORT WAYNE, INDIANA, ASSIGNEES TO S. F. BOWSER & CO., INC., OF FORT WAYNE, INDIANA, A CORPORATION OF INDIANA.

COMBINATION PUMP AND TANK.

1,109,663.

Specification of Letters Patent.

Patented Sept. 8, 1914.

Application filed October 16, 1911. Serial No. 654,805.

To all whom it may concern:

Be it known that we, DAVID A. COREY and HERBERT J. GROSVENOR, citizens of the United States, residing at Fort Wayne, in 5 the county of Allen and State of Indiana, have invented certain new and useful Improvements in Combination Pumps and Tanks, of which the following is a specification.

10 The invention relates to a combination pump and tank adapted to contain and dispense liquids and is more particularly adapted to be used for containing and dispensing liquid cement.

15 The primary object of the invention is to provide a simple, cheap and efficient combined tank and dispensing apparatus.

A further object is to provide certain improvements in the manner of connecting the 20 measuring and dispensing apparatus or pump with the tank, rendering the entire device more simple and cheap in construction and efficient in operation as well as giving the same a more slight appearance.

25 Other objects of the invention will appear in the following description of the device, the preferred form of which is illustrated in the drawings which form a part 80 of this specification.

In the said drawings, Figure 1 is a view in side elevation of the device with the lower extremity of the pump adjacent the tank and the entire tank being shown in 35 vertical section. Fig. 2 is a vertical sectional view through the device on line 2—2, of Fig. 1. Fig. 3 is a sectional view through the lower extremity of the pump on line 3—3, of Fig. 2, showing a top plan view 40 of the tank, part of the upper cover of the tank being shown broken away to disclose the hinged connection of the cover with the tank. Fig. 4 is a detail view taken on the line 4—4 of Fig. 1; and Fig. 5 is a 45 sectional view of a vent secured to the cover.

10 indicates the side walls of the tank which may be constructed of any desired form and of suitable material. In this 50 embodiment of the invention the tank is illustrated as constructed of sheet metal, the vertical walls 10 being cylindrical in form and closed at the bottom with the usual circular bottom member 11. At the 55 top the wall of sheet metal of the tank is

preferably strengthened by the metallic outer rim 12 upon which is adapted to rest the combined tank top and pump base. This tank top is preferably formed of cast metal as illustrated and is preferably nearly 60 circular in form to conform to the contour of the tank at its upper extremity, there being around the outer periphery of the plate on the lower side thereof a circumferential flange 13 adapted to register 65 with the interior of the side walls of the tank adjacent the top to form a closure when the cover is in position. This top cover is preferably secured to the tank body around its periphery by one or more suitable detachable connections as shown in 70 Figs. 2 and 3, such connections consisting preferably of the slotted projections 15 on the periphery of the top plate extending beyond the circumferential flange 12 on the 75 tank and the locking bolts 16 pivotally connected to the flange 12 of the tank at 17, there being winged nuts 18 for insertion on the threaded upper extremities of the pivoted bolts 16.

80 Heretofore in the construction of pump tanks it has been the custom to manufacture the pump and the tank separately and afterward secure them together. Such construction has not only proved objectionable 85 for several reasons but expensive as well and in the construction of our improved pump and tank the top is specially constructed with a view to utilizing the same as a part of the pump and for furnishing 90 special support to various moving parts of the pump as the piston rod and the pump control mechanism.

95 The top cover of the tank is provided with perforations for the vertical reciprocating piston rod 19, Fig. 3, and for the vertical discharge pipe of the pump, which latter is indicated by the reference character 20. The opening for the piston rod is surrounded by a circular depending flange on the under 100 side of the plate as indicated at 21, the same being of sufficient diameter and provided with an interior enlargement to receive and furnish a seat for the upper end of the pump barrel 22 which is of tubular form, preferably of brass. At the lower extremity of the pump barrel within the tank is the usual valve casing indicated by the reference character 23 and provided with a flanged portion as indicated at 24 adapted to receive and 110

close the lower extremity of the pump barrel. The valve casing 23 is preferably of an irregular form providing an inlet at 25 and a chamber for the inlet valve 26 which is of the usual puppet type of valve or of any desired construction of lift valve adapted to control the opening leading from the inlet 25 to the piston chamber, the piston being secured to the lower extremity of the piston rod 19 and being of any desired construction but without any valve controlled or other opening to permit the passage of liquid above the piston in the pump barrel, since it is desired to discharge the liquid from below the piston through the valve 27 which opens when the pressure of the piston upon the liquid within the pump barrel closes the inlet valve 26 and permits the oil under pressure from the descending piston to pass upwardly through the discharge pipe 20 of the pump and through the valve controlled nozzle 28 to be discharged from the pump. The cast top cover of the tank is further provided with a boss on the under side in the form of the peripheral flange 29 surrounding the opening for the discharge pipe 20. The member 29 is constructed as shown with an opening somewhat larger than the outside diameter of the pipe 20 and interiorly threaded to receive the upper extremity of the threaded collar 30 which is adapted to be rigidly secured to the discharge pipe 20 by set screw 31. By this construction the discharge pipe 20 may be rigidly and securely fastened to the cover plate of the tank. Its securing is further effected by means of pump bracket 32 secured to the cover at its bottom by bolts as indicated at 32', the said bracket being provided with a housing to receive the upper extremity of the rack 33 which is secured to and operates the piston rod. Within the housing at the top of bracket 32 through which passes the piston rack bar there is journaled the usual pinion 45 on shaft 34 adapted to be actuated by the usual handle 35 for imparting reciprocatory movement to the piston rod, the gear itself not being shown since it forms no part of the present invention. The upper extremity of the bracket 32 is provided with an integral collar adapted to surround the upper extremity of the discharge pipe 20 being secured to the said pipe by set screw as indicated at 36 or other suitable means.

55 The valve casing 23 at the bottom of the pump barrel within the tank is provided with a housing at the discharge side of the casing which opens upwardly and is interiorly threaded. Within this housing the valve cage 37 may be removably secured and locked in position by the hollow sleeve 38 which is suitably threaded at its lower extremity for securing to the valve casing 23, and at its upper extremity is preferably given a hexagonal shape and provided with

a threaded opening for securing to the threaded lower extremity of the vertically extending discharge pipe 20. The valve casing 23 is supported from the top cover by the vertical rods 23^a screw threaded at their upper extremities into the top cover and passing downwardly through the valve casing 23 being threaded at their lower extremities and provided with nuts. 70

By casting the tank cover of sufficient thickness to give it the necessary strength it will be seen that the entire pump construction may be very securely fixed in relation to the tank furnishing a much simpler, more economical and more durable construction than where pump and tank cover are separably and detachably constructed. It is preferred that in casting the depending peripheral flanges 21, 29 for the discharge pipe 20 and for the piston rod and the pump barrel, 85 the material may be cast solid between the flanges to afford a suitable support for a hole in which may be rotatably journaled the lower extremity of piston control rod 39, the upper end of which is likewise journaled 90 in the upper extremity of bracket 32, this rod being provided with the usual adjustably mounted control fingers 40, 41, for limiting the throw of the piston rod by engaging means as the fixed member 42 on the 95 rack bar 33.

Surrounding the opening in the top cover plate for the piston rod 19 is preferably cast integrally with the plate an upwardly extending flange forming a suitable packing gland around the piston rod, as indicated at 43, the same being threaded exteriorly to receive clamping nut 44 which cooperates to bind the upper member 45 of the gland upon suitable packing material contained within the gland. In order that the top cover of the tank may be liquid tight, suitable packing as indicated at 46 may be placed around the discharge pipe 20 at the point it passes through the cover between the cover flange 29 and the threaded locking member 30 to close the joint between the cover and the pipe at this point. For filling the tank without removing the top cover plate an opening in the cover plate, as indicated at 47, may be provided, this opening to have a cover as indicated at 48 secured by means of winged nuts and cooperating bolts as shown in Figs. 2 and 3. The exterior bolt and nut may be an extension of one 110 of the hinged bolts 16 with its winged nut 18 while at the inside separate fastening means as indicated at 49 is provided.

A vent pipe 51 is secured in any suitable manner to the cover and a T 50 is preferably mounted upon the outer end of the vent pipe 51, the open ends of the T being provided with screens 52 and 53, which may be of any desired or suitable reticulated material and which are adapted to permit the egress of 115

vapors and gases from a tank and to prevent the ingress of objectionable materials, as well as to prevent fire from entering the tank.

- 5 The operation of the device does not differ from that of the ordinary pump tank, the material to be dispensed being introduced through the opening beneath the removable cover 48 and discharged through the pump 10 nozzle by the operation of the pump piston actuated by handle 25, the amount of liquid to be dispensed being predetermined either by limiting the operation of the piston through the control rod 39 and stops there- 15 on or by the number of total reciprocations of the piston or by combination of total reciprocations and fractional measurements due to limiting the movement of the piston by the controlling means described.
- 20 It is not desired to be limited to the exact details of construction since it will be apparent that certain modifications may be adopted by those skilled in the art without departing from the purpose and spirit of 25 the invention.

We claim:

In a liquid dispensing apparatus the combination with a closed tank of a single cast metal cover therefor formed with a depend- 30 ing flange to fit the inside of the tank, the

said cover being provided with openings therethrough, some of said openings being surrounded above and below the cover with annular projections forming packing gland cases and one of said openings being adjacent the periphery of said cover, the edges of the cover being formed with slots, hinged clamping bolts secured to the tank adjacent the top thereof and adapted to be pivotally swung into engagement with the slots of 35 said cover, winged nuts to engage said bolts to bind the cover in position and a lid for the said opening adjacent the periphery of the cover adapted, when in closed position, to be engaged on one side by one of the 40 winged nuts for securing the cover in position, and a separate winged nut inserted through the other side of the lid into the cover for securing the lid firmly in position.

In testimony whereof we have signed our names to this Specification, in the presence of two subscribing witnesses, on this 7th day of September A. D. 1911.
